UNITED STATES PATENT OFFICE.

JOHN HEITMAN, OF SEATTLE, WASHINGTON.

PHONOGRAPH-RECORD CABINET.

1,397,517.

Specification of Letters Patent. Patented Nov. 22, 1921.

Application filed November 8, 1920. Serial No. 422,623.

To all whom it may concern:

Be it known that I, JOHN HEITMAN, a citizen of the United States, and resident of Seattle, in the county of King and State 5 of Washington, have made certain new and useful Improvements in Phonograph-Record Cabinets, of which the following is a specification.

This invention relates to phonograph record cabinets and more particularly to the record ejecting means.

Briefly stated, this invention aims to provide a phonograph record cabinet having simple means whereby the desired record 15 may be projected to a position from where it may be entirely removed from the cabinet.

A further object of the invention is to provide a phonograph record cabinet having novel means whereby the ejecting mechanism 20 is rendered inoperative while one of the records is removed from the cabinet so as to prevent the removal of additional records until the record which has already been removed is replaced.

25 A further object of the invention is to provide a phonograph record cabinet having means whereby the zone of action of the ejector mechanism may be regulated in proportion to the number of records contained 30 within the cabinet.

The invention forming the subject matter of this application aims also to provide a phonograph record cabinet having an ejecting mechanism which is simple to operate, durable in use and cheap to manufacture.

Other objects and advantages of the invention will be apparent during the course of the following description.

40 In the accompanying drawings forming a part of this application and in which like numerals are employed to designate like parts throughout the same,

Figure 1 is a side elevation of a record cabinet having the improved record ejecting mechanism, parts of the cabinet being shown in section.

Fig. 2 is a front elevation of a phonograph cabinet having the improved record ejecting mechanism, parts of the cabinet being shown in section.

Fig. 3 is a detail sectional view through the cabinet, the view illustrating the operating means for the ejector.

55 Fig. 4 is a detail sectional view taken on line 4-4 of Fig. 3.

Fig. 5 is a vertical detail sectional view through the cabinet, the view illustrating the indicating and ejecting means.

Fig. 6 is a fragmentary rear elevation of 60 the cabinet, and

Fig. 7 is a fragmentary perspective of a rock shaft embodied in the invention, the shaft being shown provided with an adjustable stop element.

In the drawings wherein for the purpose of illustration is shown a preferred embodiment of the invention the numeral 10 designates a cabinet or casing within which a number of records are adapted to be received. As illustrated in Fig. 2 the front side of the cabinet may be provided with doors 12 which extend over the enlarged ends of a concealed horn of a record playing device. However, the record playing device forms no part of the present invention and in fact the present invention may be carried out in a cabinet solely adapted for receiving the records.

With reference to Figs. 1 and 2 it will be 80 noted that the cabinet is provided with a plurality of upstanding spaced parallel partitions 14 which define compartments 16 adapted for the reception of disk records. The front side of the cabinet is provided 85 with one or more hinged doors 18 which may be opened to afford access to the disk records contained within the compartments 16.

As illustrated in Figs. 1 and 5 a carriage 90 20 is slidable within each compartment 16 and has its upper portion recessed to form a seat upon which a disk record is adapted to be mounted. The seat formed by curving or recessing the upper portion of the carriage conforms to the curvature of the disk so that the disk is prevented from accidentally rolling out of the cabinet either when in an extended or retracted position. Carriages of various sizes may be provided 100 to accommodate records of various sizes. Each carriage may be removed and replaced by one of a larger or smaller size by opening the door 22 in the rear side of the case. The rear portion of each carriage is pro-

vided with an opening 24 by means of which a hook may be connected to the carriage for removing the same. Each carriage is held in an upright position by reason of its contact with the adjacent walls of the partitions. However, each carriage must be slightly elevated prior to its removal so as

to clear a strip 26 which extends across the bottom of the cabinet.

The disk records may be moved to an advanced position by imparting a corresponding movement to the carriages. When in advanced position, the record has one edge portion extended beyond the partitions 14 so that the same may be gripped by the fingers for entire removal.

10 The means employed for advancing the carriages singly comprise a transversely extending rock shaft 28 which has its end portions rounded as indicated at 30 and rotatably supported. As illustrated in Fig. 5
15 an ejector 32 is slidably and non-rotatably mounted on the squared shaft 28 and is adapted to be engaged with the rear sides of downwardly extending lugs 34 formed at the forward ends of extensions 36 carried by
20 and formed integral with the carriages. When an anti-clockwise movement is imparted to ejector 32 the curved end portion of the same is engaged with the downwardly extending lug 34 whereby the carriage to
25 which the lug 34 is connected is moved forwardly or to an advanced position. The forward movement of the carriage is limited by means of a shoulder 37 which engages the rear edge of a transversely extending
30 stop element 38 arranged adjacent the forward side of the casing. When in the position illustrated in dotted lines in Fig. 5 the ejector 32 is prevented from sliding movement on the shaft by reason of the fact that
35 the partitions 14 are extended forwardly beneath the transversely extending strip 38 as indicated at 40 and between which the ejector is located when advanced. Therefore when the carriage is moved forwardly
40 by the ejector no further records may be extracted until the first record has been replaced within the compartment from which it was taken. When the record is replaced the carriage is moved rearwardly thereby
45 swinging the ejector in a clockwise direction so as to clear the extensions 40 of the partitions 14.

With reference to Fig. 3 it will be noted that a trigger 42 is rigidly connected to the
50 squared shaft 28 at one end of the same and is provided at its upper end with a laterally projecting lug 44 which is engaged by a longitudinally curved operating handle or lever 46 when the latter is moved forwardly or in
55 an anti-clockwise direction. The lower portion of the trigger 42 is provided with a laterally projecting lobe 47 with which a leaf spring 48 contacts so as to swing the trigger as far as possible to the right when a slight
60 clockwise movement is imparted to the shaft 28 by the rearward movement of the carriage. Since the spring 48 swings the trigger to the limit of its movement to the right the ejector 32 is swung out of contact with
65 the adjacent downwardly extending lug car-

ried by the extension 36 of the carriage. With the ejector thus spaced from contact with the adjacent lug 34 and of course from the other lugs the ejector may be freely moved along the shaft for adjustment behind any one of the depending lugs 34. 70

As illustrated in Fig. 4 it will be observed that the lever or operating handle 46 is rotatably supported by the rounded end portion 30 of the shaft 28 and is slidable 75 through a slot 50 in the supporting member 52 in the form of a metallic plate. The free end portions of the operating handle 46 is curved longitudinally and is extended forwardly to a point from which the same 80 may be readily engaged by a person desiring to remove a record from the cabinet. When the lever or operating handle 46 is moved forwardly a corresponding movement is imparted to the trigger 42. When the trigger 85 42 passes the upright position the spring 48 will by reason of its contact with the lobe 47 swing the trigger rapidly to the limit of its anti-clockwise movement. This, of course, will advance the desired record to 90 a point from where the same may be readily removed.

The ejector 32 may be moved along the squared shaft 28 to a point rearwardly of any one of the depending lugs 34 by means 95 of an indicator 52 which is connected to the ejector. A portion of the indicator is extended exteriorly of the casing and is provided with a combined adjusting member and pointer 54 which plays over an index 100 on the front side of the cabinet. The indicator is slidable through the slot 56 which extends transversely of the indicator and which is formed in a front plate 58. 105

In the use of the improved record cabinet 110 a number of disk records are placed within the compartments 16 so that the same will be mounted upon the carriages 20. The carriages 20 of the proper size will be provided, that is to say, a certain sized carriage will 115 be provided for a ten inch record while a larger carriage will be provided for a twelve inch record. Should there be an insufficient number of records to completely fill the compartments 16 only the compartments adjacent one end of the cabinet may be used and the zone of action of the ejector 32 may be reduced by means of a collar 60 slidable on the squared shaft 28 and provided with a set screw 62 by means of which the 120 collar may be securely though adjustably connected to the shaft.

Should it be desired to remove record No. 6 or any other record, the pointer 54 will be moved along the indicator to the proper 125 compartment whereby the ejector 32 will be positioned behind and in spaced relation to the depending lug 34 of the carriage supporting the desired record. By pushing the lever or operating handle 46 forwardly the 130

trigger will be correspondingly moved with the result that the ejector 32 will be advanced thereby engaging the depending lug 34 and moving the same forwardly. The 5 forward movement of the carriage is limited by means of a shoulder 37 which engages the rear side of the stop element 38. As previously stated the sliding movement of the ejector 32 on the shaft 28 is prevented 10 during the period of the removal of the disk. This prevents more than one record from being removed at a time.

With reference to the foregoing description taken in connection with the accompanying drawing it will be apparent that 15 ejecting mechanism for phonograph record cabinets constructed in accordance with this invention will be simple to operate and will admirably perform the desired functions.

20 Having thus fully described the invention, what I claim is:

1. A record cabinet comprising a casing having a plurality of partitions defining compartments, spaced parallel carriages 25 slidable within said compartments and having lugs, an ejector adapted to singly engage said lugs for advancing said carriages, a rock shaft slidably supporting said ejector, operating means for said ejector associated with 30 said rock shaft, the upper sides of said carriages being formed with shoulders, said casing being provided with a transversely extending stop element arranged in the path of travel of said shoulders whereby to limit 35 the movement of said carriages, and an adjusting device for said ejector.

2. In a cabinet, the combination of a plurality of sliding article supporting carriages having extensions formed with depending 40 lugs, and an ejector adapted to separately engage said lugs for advancing said carriages, said carriages being formed with shoulders constituting stop elements limiting the forward movement of said carriages.

45 3. In a cabinet, the combination with a casing, of carriages slidable therein, a single ejector adapted for singly advancing said carriages, means to secure said ejector in a set position when one of the carriages is advanced, and a spring normally spacing 50 said ejector from said carriages.

4. A record cabinet having a plurality of partitions forming compartments, carriages slidable within said compartments and having lugs, a slidably supported ejector movable rearwardly of said lugs and adapted to engage the same, and operating means for 55 said ejector.

5. A record cabinet having a plurality of 60 partitions forming compartments, carriages slidable within said compartments and having lugs, a slidably supported ejector movable rearwardly of said lugs and adapted to engage the same, and operating means for 65 said ejector, said ejector being adapted to

swing between said partitions when advanced.

6. A record cabinet comprising a casing, carriages slidable within said casing and provided with lugs, a shaft, an ejector slidable 70 on said shaft and adapted for engagement with said lugs, means whereby said ejector may be advanced for advancing said carriages, and means for spacing said ejector from said lugs when the ejector is retracted. 75

7. A record cabinet comprising a casing, carriages slidable within said casing and provided with seats, said carriages being provided with depending lugs, a shaft, an ejector slidable on said shaft and adapted for 80 engagement with said lugs, means whereby said ejector may be advanced for advancing said carriages, means for spacing said ejector from said lugs when the ejector is retracted, and an adjusting device for said 85 ejector.

8. A cabinet comprising a carriage having a forwardly extending portion provided with a lug, a shaft, an ejector slidably and non-rotatably mounted on said shaft and 90 adapted to engage said lug, operating means connected to said shaft for advancing said ejector, and means to limit the forward movement of said carriage.

9. The combination with a casing, of carriages therein, a swinging and slidable ejector for said carriages, means holding the ejector against sliding movement when advanced, means normally spacing said ejector from the carriages, and an adjusting 100 device for positioning said ejector adjacent the carriage to be advanced.

10. The combination with a casing, of carriages therein, a swinging and slidable ejector for said carriages, a shaft slidably supporting said ejector, means holding the ejector against sliding movement when advanced, 105 a spring normally spacing said ejector from said carriages, and an operating device for said shaft.

11. The combination with a casing, of carriages therein, a swinging and slidable ejector for said carriages, means holding the ejector against sliding movement when advanced, and a spring spacing said ejector 115 from said carriages when the ejector is retracted.

12. A record cabinet comprising a case, carriages slidable with the case, a transversely extending shaft, an ejector mounted 120 on said shaft and cooperating with said carriages, a trigger secured on said shaft, and an operating handle rotatably supported and having contact with said trigger for advancing the same.

13. A record cabinet comprising a case, carriages mounted within the same, a shaft, an ejector mounted on said shaft and cooperating with the carriages, a trigger secured on said shaft and provided with a 130

lobe, a spring engaging said lobe for urging the trigger to its extreme position, and operating means for said trigger.

14. A record cabinet comprising a case, 5 carriages mounted within the same, a shaft, an ejector mounted on said shaft and cooperating with the carriages, a trigger secured on said shaft and provided with a lobe, a spring engaging said lobe for urging 10 the trigger to its extreme positions, operating means for said trigger, and adjusting means for said ejector.

15. A record cabinet comprising a case, 15 carriages mounted within the same and provided with forwardly extending portions having lugs, a shaft traversing the case, an ejector slidable on said shaft and adapted to engage said lugs, a trigger secured to said shaft and provided with a lobe, a spring engaging 20 said lobe to urge the trigger to its extreme positions and operating means associated with said trigger.

16. An apparatus of the class described comprising a carriage having an extension, 25 an ejector arm adapted to engage said extension, operating and supporting means for said ejector arm, and a spring associated with said operating and supporting means for normally spacing said ejector from said 30 carriage.

17. An apparatus of the class described

comprising a carriage having an extension, an ejector arm adapted to engage said extension, a rock shaft slidable and non-rotatably supporting said ejector arm, and spring means associated with said rock shaft for normally spacing said ejector arm from said extension. 35

18. An article cabinet comprising partitions, and an article ejector movable to its 40 advanced position between said partitions whereby the ejector is held against transverse movement when advanced.

19. An article cabinet comprising partitions, an article ejector movable to its 45 advanced position between the partitions, whereby the ejector is held against transverse movement when advanced, and an adjusting device for said ejector.

20. An article cabinet comprising partitions, an article ejector movable to its 50 advanced position between the partitions, whereby the ejector is held against transverse movement when advanced, an adjusting device for said ejector, and operating 55 means for said ejector.

21. An article cabinet comprising a rock shaft having an ejector, a trigger secured to said shaft, means detachably holding the trigger in its extreme position, and an operating member for said trigger. 60

JOHN HEITMAN.
